(57) **CLAIM**

The ornamental design for a back panel of a case for an electronic device, substantially as shown and described.

DESCRIPTION

FIG. 1 is a perspective view of a back panel of a case for an electronic communications device according to the design. FIG. 2 is a back view showing the back panel of the case for an electronic communications device of FIG. 1.

FIG. 3 is a first side view of the back panel of the case for an electronic communications device of FIG. 1.

FIG. 4 is a top view of the back panel of the case for an electronic communications device of FIG. 1.

FIG. 5 is a front view of the back panel of the case for an electronic communications device of FIG. 1.

FIG. 6 is a bottom view of the back panel of the case for an electronic communications device of FIG. 1; and,

FIG. 7 is a second side view of the back panel of the case for an electronic communications device of FIG. 1.

The regions shown in broken lines represent portions of the case that form no part of the claimed design.

1 Claim, 3 Drawing Sheets
